UNITED STATES PATENT OFFICE

2,459,774

WATER COOLER WITH A DRAIN
ARRANGEMENTSamuel O. Morrison, Media, Pa., assignor to
Sunroc Refrigeration Company, Dover, Del., a
corporation of Delaware

Application June 26, 1946, Serial No. 679,505.

4 Claims. (Cl. 62—141)

1

My invention relates to water coolers or drinking fountains.

A purpose of my invention is to eliminate a cause of intermittent unpleasant taste and odor in water dispensed from water coolers.

A further purpose is to prevent the serving of slugs of dead water.

A further purpose is to lead the water connection from the water cooling unit to the water dispenser via the drain fitting, suitably adjacent a wall of the cooler cabinet.

A further purpose is to provide the outlet of a water cooling unit suitably of vertical coil type at the bottom, and to lead the water from the outlet first downward to a drain fitting before leading it upward to a water dispenser.

A further purpose where a plurality of dispensers are used is to lead the water from the cooling unit first to a drain fitting preferably accessible from outside the cooler before branching to the individual dispensers.

Further purposes appear in the specification and in the claims.

In the drawings I have chosen to illustrate one only of the numerous embodiments in which my invention may appear, the form shown being chosen from the standpoints of convenience in illustration, satisfactory operating and clear demonstration of the principles involved.

Figure 1 is a rear elevation, partially diagrammatic, of a water cooler to which my invention is applied.

Figure 1a is a diagrammatic top plan view, partly in section, showing my invention applied to a water cooler.

Figure 2 is a rear elevation of the drain fitting of the invention.

Figure 3 is a side elevation of the drain fitting of Figure 2.

Figure 4 is a section on the line 4—4 of Figure 2.

Figure 5 is a section through a single turn of the unit, taken on the line 5—5 of Figure 1.

Describing in illustration but not in limitation and referring to the drawings:

In prior art water coolers, sometimes called drinking fountains, of the type which cool a stream or a body of drinking water and supply it to a dispenser, there have been intermittent complaints that an individual user has been supplied with a drink of water which has an unpleasant taste or odor. On investigation of such complaints, it was commonly found that the condition could not be duplicated at the cooler about which complaint had been made, and the cause

2

was ascribed to a personal peculiarity of the individual user, or a condition present in the local drinking water supply or distribution system.

However, such complaints would recur at irregular intervals and in widely separated localities, and I was accordingly led to reexamine the water cooler construction to see whether any materials used in the piping, chemicals used in soldering or welding, dissimilar metals, concentration cell corrosion due to dissolved oxygen or other gases, attack by or deposit of minerals from the water, local condition of hardness, chlorination or any other cause was responsible for this condition.

Surprisingly, I found after exhausting numerous possibilities that the cause was not corrosion, nor related to the materials used, but was a matter of design which, once its importance was discovered, could be readily corrected.

20 In the prior art practice, as shown in part of Figure 1, the water cooler consists of a cabinet 20 having a base 21, side walls 22 and a top 23, provided with one or more dispensers 24, suitably a bubbler 25 and a drinking glass faucet 26. The top has a catch basin 27, connecting with a sump 28, having a waste pipe 29, to a waste connection fitting 30 connected with the plumbing.

25 Inlet drinking water from any suitable source enters inlet fitting 31 and flows by pipe 32 through the sump 28 to be precooled by the waste water, and thence by pipe 33 to a cooling unit 34, having separate interior passages, as shown, for water and refrigerant. From the cooling unit, the drinking water was in the prior art (unlike Figure 1) conducted directly to the dispenser or dispensers. Also from some low point in the system, a spur pipe was in the prior art run to a drainage fitting adjacent a wall 22 of the cabinet. I find that it is this spur pipe which has caused the difficulty. Apparently, since the water in this spur pipe has been largely inactive or non-circulating, bacteriological, mycological or chemical effects have taken place in such water, due to organisms and/or ingredients of the water. 30 Eventually in some cases the water in the spur pipe has become unpleasant in taste or odor. Occasionally, due to an unusual pressure or flow relation, a body of air carried by the water stream, or some other cause, a slug of this water from the spur pipe has been fed to the dispenser, and complaints have resulted.

35 By changing the design, difficulty from this cause has been eliminated. I make the inlet water connection 33 to the water passage 34' of the water cooling unit 34 at the top and provide

a water outlet 35 at the bottom. From the water outlet 35 I avoid direct connection to the dispenser as in the prior art, but instead lead a pipe 36 downwardly from the outlet 35 to a drainage fitting 37, adjacent a wall 22 of the cabinet 20.

The drainage fitting 37 is located at the lowest point of the drinking water system of the cooler to permit drainage to prevent freezing when the water is cut off or the cooler is moved or shipped. From the drainage fitting 37, connection is provided to the dispenser or dispensers, here pipe 38 to bubbler 25 and pipe 39 to faucet 26. In this layout, all water to the dispensers passes directly through the drainage fitting and no longer is there any spur pipe to accumulate inactive water and develop taste or odor.

Refrigerant to pass through the refrigerant passage 34² of the cooling unit (coil) is provided as from a mechanical refrigeration unit at 40 having a refrigerant supply line 41 through a valve 42 to the bottom of the vertical coil, and a refrigerant return line 43 from the top of the coil. The detail of the refrigeration unit and connections is of course not part of the present invention.

Figures 1^a to 4 show more clearly the preferred arrangement. The drain fitting 37 has an inlet 44 for the pipe 36 from the cooling unit 34 (here shown of tank type), and outlets 45 and 46 arranged in a deformed Y to connect to pipe 38 to bubbler 25 and pipe 39 to faucet 26.

A boss 47 extends through a hole 48 in the cabinet wall 22, receiving a drain plug 49 in its pipe thread 50. The drain plug is accessible from outside the cabinet to drain the water when the cooler is shut off.

Flanges 51 around the boss inside the wall 24 carry openings 52 for bolts 53 to fasten the drain fitting to the wall.

By the present invention, it will be evident that no dead water space is provided inside the drain fitting at 54, or in any of the piping.

In view of my invention and disclosure variations and modifications to meet individual whim or particular need will doubtless become evident to others skilled in the art, to obtain all or part of the benefits of my invention without copying the structure shown, and I therefore claim all such insofar as they fall within the reasonable spirit and scope of my claims.

Having thus described my invention what I claim as new and desire to secure by Letters Patent is:

1. In a water cooler, a drinking water dispenser, a water cooling unit below the dispenser, a drain fitting below the water cooling unit, an inlet connection for water to the cooling unit, a connection leading from the bottom of the cooling unit downward to the drain fitting and a connection leading upward from the drain fitting to the dispenser.

2. In a water cooler, a cooler cabinet, a drinking water dispenser at the top of the cabinet, a water cooling unit in the cabinet below the dispenser, means for supplying drinking water to the cooling unit, a drain fitting below the cooling unit and adjacent one wall of the cabinet, a water connection from the cooling unit to the drain fitting and a water connection from the drain fitting to the water dispenser.

3. In a water cooler, a cooler cabinet, a plurality of drinking water dispensers at the top of the cabinet, a water cooling unit in the cabinet below the dispensers, means for supplying drinking water to the cooling unit, a drain fitting below the cooling unit and accessible for opening from outside the cabinet, a water connection from the bottom of the cooling unit extending downward to the drain fitting, and connections extending upward from the drain fitting to the individual dispensers.

4. In a water cooler, a dispenser, a vertical coil water cooling unit having water carrying passages in the coil below the dispenser, means for introducing water to be cooled at the top of the coil cooling unit, a drain fitting below the bottom of the coil cooling unit, a water connection extending downward from the bottom of the coil cooling unit to the drain fitting and a water connection extending upward from the drain fitting to the dispenser.

SAMUEL O. MORRISON.
